United States Patent Office

Des. 210,939
Patented May 7, 1968

210,939

CHAIR

George M. Schwarz, Jr., Portland, Oreg., assignor to
Gold Medal Folding Furniture Co., Racine, Wis., a
corporation of Wisconsin

Filed Dec. 19, 1966, Ser. No. 5,075

Term of patent 14 years

(Cl. D15—1)

FIGURE 1 is a perspective view of a chair embodying my new design and taken generally from the front, right corner thereof;

FIGURE 2 is a front perspective view of the chair;
FIGURE 3 is a right side perspective view of the chair;
FIGURE 4 is a rear elevational view of the chair;
FIGURE 5 is a plan view of the chair.

The chair is characterized by upwardly and outwardly angled front and rear leg members in combination with the upwardly and forwardly inclined seat rail, all as shown.

I claim:

The ornamental design for a chair, substantially as shown and described.
